BOAT PROPELLER

Otto L. Bihlmire, Sisters Lake, Mich.

Filed July 9, 1958, Ser. No. 51,704

Term of patent 14 years

(Cl. D71—1)

FIG. 1

FIG.2

FIG.3

FIG.4

FIG.5

FIG. 1 is a front elevation of a boat propeller embodying my new design;

FIG. 2 is a rear elevation thereof;

FIG. 3 is a fragmentary side view thereof; slightly in perspective, the blades being broken away for convenience of illustration only.

FIGS. 4 and 5 are cross-sectional views taken on the lines 4—4 and 5—5 of FIG. 1.

I claim:

The ornamental design for a boat propeller, substantially as shown.
